TEXTILE MECHANISM

Edward J. Abbott and Winthrop L. Perry, Wilton, N. H., assignors, by mesne assignments, to Abbott Worsted Mills, Incorporated, Wilton, N. H., a corporation of New Hampshire

Application August 17, 1948, Serial No. 44,754

14 Claims. (Cl. 242—35.5)

1 This invention relates to textile mechanism and more particularly to improved mechanism for arranging textile packages, adapted for combination with mechanism which delivers such wound packages, such as an automatic winding machine or machines.

Among the principal objects of the invention are to provide mechanism which will handle the packages gently, guarding them against damage, but capable of keeping pace with a rapid stream of production of packages, for example, the product of a large group of automatic winding units. Thus, one object of the invention is to concentrate the operations of arranging the packages in a single mechanism adapted to serve a considerable number of winding units, and to gather together and systematically arrange the packages from such winding units at a convenient place. The invention contemplates the accurate and careful construction of the package arranging mechanism because of the need for gentle handling of individual packages, such as packages of fine delicate filaments, but provides economy of operation because of the large number of winding units with which a single such mechanism of the present invention can conveniently operate.

The invention aims to provide for a reliable automatic supply of a large number of package holders, such as pins of pinboards, necessary to receive a large volume of production of packages, but aims to reduce to the minimum the amount of supervision and attention required of the operator.

The invention further aims to guard against any voids or vacancies among the automatically filled package holders, such as might be occasioned by one or more of the many winding units being idle. The invention also aims to prevent any uncontrolled discharge of packages such as might occur in the event that the supply of empty package holders became exhausted.

Other objects and advantages of the invention will be apparent from this specification and its drawings in which the invention is explained by way of example.

In the accompanying drawings,

Fig. 1 is a front elevation of bobbin-arranging mechanism shown as combined with a traveling spindle filling bobbin winder, only a fragment of the winder being shown;

Fig. 2 is a view from the right of Fig. 1, partly in elevation and partly in vertical section, bobbins being omitted from the pins of the pin-

boards and bobbin-arranging mechanism in this view;

Fig. 3 is a plan of the apparatus of Figs. 1 and 2, all but one of the many winding units being omitted;

Fig. 4 is a schematic diagram showing one of the package carriers in receiving position and showing a package-delivering cradle in two positions, and also an electric switch responsive to the reception of a package by the cradle;

Fig. 5 is a fragmentary view in the nature of a vertical section taken on the line 5—5 of Fig. 3 or of Fig. 4 with various parts omitted, and showing a package having just rolled from the bobbin-supporting plate of the winding machine onto the package-delivering cradle;

Fig. 6 is a view similar to Fig. 5 but taken on the line 6—6 of Fig. 4 showing the package having been rolled from the cradle into a horizontally disposed package carrier;

Fig. 7 is a view from the same point of view as Fig. 2 but on a larger scale and with many parts broken away or removed, showing driving mechanism for the package-delivering cradle and for the plurality of package carriers, and showing the gate adapted to control discharge of the packages from the package carriers;

Fig. 8 is a vertical sectional view, partly in elevation, on the line 8—8 of Fig. 7;

Fig. 9 is a vertical sectional view on the line 9—9 of Fig. 7;

Fig. 10 is a detail, mainly in plan, showing Geneva gearing of Figs. 7, 8 and 9;

Fig. 11 is a detail, mainly in vertical section, of a one revolution clutch of Figs. 1 and 2;

Fig. 12 is a fragmentary view, mainly in plan, showing a package holder, in the form of a pinboard, held in place on its conveyor for reception of a group of packages by a row of its pins;

Fig. 13 is a fragmentary elevation taken from the left side of Fig. 12, showing also two of the package carriers and the gate;

Fig. 14 is a wiring diagram of the bobbin-arranging mechanism as combined with a traveling spindle filling bobbin winder;

Fig. 15 is a fragmentary view in right elevation, taken on the line 15—15 of Fig. 1 showing mechanism for removing pinboards from a reserve stack, the elevator plate of such mechanism being fully lowered;

Fig. 16 is a fragmentary view, from the same point of view as Fig. 15, showing the elevator plate fully raised, the lowermost pinboard of Fig. 15 having advanced out of the way of the elevator plate;

Fig. 17 is a view similar to Fig. 16 showing the elevator plate partly lowered from its position of Fig. 16;

Fig. 18 is a fragmentary view in plan, but at a later time in the operation of filling a pinboard than is shown in Fig. 3, showing a further pinboard brought by the conveyor chains into abutting relation to the rear end of the pinboard being filled;

Fig. 19 is a plan view, largely diagrammatic, of a bobbin-arranging mechanism combined with a group of automatic stationary spindle filling bobbin winding units, only a few of the many such units being shown;

Fig. 20 is a diagrammatic view from the right of Fig. 19, with many parts omitted;

Fig. 21 is a diagrammatic front elevation of a portion of the apparatus of Figs. 19 and 20; and

Fig. 22 is a detail view showing switch actuating mechanism of the apparatus of Figs. 19 to 21.

Although the invention is applicable to arranging various types of textile packages, the invention will be explained by way of example as applied to arranging packages which consist of bobbins of filling-wound yarn. In Figs. 1 to 18, the bobbin-arranging mechanism is shown as combined with a traveling spindle filling bobbin winder, which combination is advantageous, and in Figs. 19 to 22 similar mechanism is shown as combined in somewhat different manner with a group of stationary spindle filling bobbin winding units.

Various constructions of package holders, onto which the packages are arranged, may be employed. The simplest of such package holders are the individual bobbin-holding pins of pinboards. As shown in Figs. 1, 2, 3, 12 and 13, a pinboard may for example comprise a flat bottom pin from which several rows of bobbin-holding pins project upwardly. In the form shown each pinboard includes ten rows of pins, each row consisting of eight pins. Each pin is adapted to hold a filling wound bobbin by extending up into the bottom opening of the bobbin.

Such pinboards are supported as subsequently described and are moved from left to right in Figs. 1, 3, 13 and 18 or toward the observer in Figs. 2 and 15 to receive the wound packages, or more specifically filling-wound bobbins, upon their several pins.

The traveling spindle filling bobbin winder of which a portion is shown in Figs. 1, 2 and 3 may include many of the features of Reissue Patent No. 22,492 and Patents Nos. 2,362,455, 2,377,367, 2,395,028, 2,426,167 and 2,426,168. Thus the winder may include a plurality of winding units indicated generally at 15 movable around an endless track consisting of upper and lower stationary rails 16 and 17 by means of an endless chain 18 (Fig. 3). Each winding unit may be individually driven by its own electric motor 19 deriving its current through the frame of the machine and through suitable brushes contacting with stationary conductor bars 20, so as to wind an individual yarn package as the winding unit travels around the machine.

Yarn Y from a supply package carried by the unit may be drawn upwardly through suitable tension devices 21 and through a breakage detector 22 to a traversing thread guide assembly indicated at 23, and thence onto a winding bobbin held between inner and outer centers 24 and 25.

The inner center 24 is rotated by the motor 19 to rotate the bobbin. The thread guide assembly

23 is reciprocated by suitable cam and linkage connections also driven by the motor, and, during the winding, the thread guide assembly is progressively advanced from the base of the bobbin toward the tip, to provide the typical filling wind.

Upon the completion of a wound package by the winding unit, winding is stopped and the individual motor of the unit is de-energized by breaking the circuit to the motor, for instance by lifting of the unit's brushes from the conductor bars 20. This action should normally occur somewhat before the winding unit reaches the apparatus shown in Figs. 1 and 3. Preferably the machine is provided with a known form of mechanism which will deenergize the individual motor at such place in any event, whether or not the package has been completed. It will therefore be understood that the winding units enter the apparatus particularly shown in Figs. 1, 2 and 3 in an inactive condition but still holding the wound bobbin in winding position between the centers 24 and 25.

The outer center 25 of each unit is retractable to discharge the wound package from winding position by means of a crank arm 30 on the winding unit and a stationary abutment 31 diagrammatically indicated on Fig. 3. Upon the crank arm 30 encountering the abutment 31, the wound bobbin will drop from the centers a short distance onto a horizontal stationary plate 32 which extends along the path of travel of the winding units 15, underneath their head portions. The bobbin is rolled along this plate by being held between a vertical plate 35 and a rod 36 (Fig. 2) both of which extend from and move along with the winding unit.

When the crank 30 leaves the right end of abutment 31 in Fig. 3, the outer center 25 is allowed to close upon a new empty bobbin appropriately held by suitable bobbin-feeding mechanism located in this region, the bobbin-feeding mechanism being omitted from these drawings for clarity of illustration but a line b—b indicating the center line at which a new empty bobbin is held by the bobbin-feeding mechanism. In Fig. 2 a new empty bobbin B is shown as having been received between the centers 24 and 25, in winding position, and above the discharged full bobbin which is being rolled along on the plate 32, and in Fig. 3 this new empty bobbin in winding position has been broken away to show the discharged full bobbin below it.

From the right end of the plate 32 the packages roll singly and successively onto a package-delivering cradle 40 adapted to deliver the packages singly and successively to further package-arranging mechanism subsequently described which effects a distribution of the successively-received packages with relation to the pins of a pinboard, in two directions, that is, crosswise and lengthwise of the pinboard, so as to fill the plurality of rows of pins of the pinboard. Preferably this distribution involves distributing packages to the individual pins of a row, then to the individual pins of the next row, and so on to individual pins of successive further rows. Distribution within a given row is preferably accomplished by carrying the successive packages different distances along that row so that the respective packages are aligned with the respective pins of that row, and distribution as between successive rows is preferably accomplished by relative shift between the package-receiving means and the pinboard.

Discharge of the packages distributed over one

row of pins preferably takes place simultaneously, upon the arrival of a complete row of packages each in position to be discharged to a corresponding pin of the row. This permits packages to be carried to their distributed positions in relatively short steps or without any rapid motion, several packages moving simultaneously, and all the packages of a row simultaneously reaching positions in alignment with the pins onto which they are to be received.

The package-arranging mechanism preferably includes a plurality of individual package carriers 41 in the form of open-ended chutes or troughs movable in an endless path outside the path of travel of the winding units.

In Figs. 1, 2 and 3 the cradle 40 is shown in its receiving position about to receive a bobbin from the plate 32. In Fig. 4 the cradle 40 is shown in full lines in its delivery position adjacent to the package carrier 41 to which it has just delivered a bobbin, and also in broken lines in its package-receiving position.

For shifting the cradle between its two extreme positions of Fig. 4, a cross rod 45 on which the cradle tilts, is fixed in blocks 46 at each end, the two such blocks being connected by vertical pivots to horizontal parallel links 49 which in turn are pivotally mounted at 50 upon a stationary part of the machine. An extension 50a extending from one of the links 50 is connected by a link 52 to a crank disk 53 which is intermittently rotated, as subsequently described, carrying the cradle from its broken line position of Fig. 4 to its full line position and back to such broken line position in one revolution of the crank disk.

The cradle carries a downwardly extending arm 54 carrying a roller 55 adapted to roll along a guide surface 56 to determine the inclination of the cradle. As shown in Fig. 5 at the receiving position of the cradle, and also throughout most of its travel toward its discharging position, the guide surface 56, acting through roller 55, holds the cradle approximately horizontal. However, close to the discharging position shown in Fig. 6 and in full lines in Fig. 4, the guide surface 56 retreats, permitting the cradle to tilt to the inclination shown in Fig. 6 to roll the package onto the package carrier 41.

The machine preferably includes means adapted to detect the presence of a newly arriving package, to be arranged, and upon such detection to set in motion a single-cycle drive for various of the parts of the mechanism. In the preferred form of the invention such detector includes a normally open microswitch 57, Figs. 4 and 5, having an actuating arm 58 located in position to be engaged by the roller 55 of the cradle in the package-receiving position of the latter. When a bobbin rolls off the plate 32 onto the cradle, the cradle is slightly tilted by the weight of the bobbin, acting through the roller 55 and actuating arm 58 to close the microswitch 57. As subsequently described with reference to the wiring diagram of Fig. 14, this initiates a cycle of operation of various parts, including rotation of the crank disk 53 and delivery of the bobbin to a horizontally disposed package carrier 41.

In the preferred form of apparatus in which a group of eight packages, corresponding in number to the pins of a row, are brought into position over the respective pins and then discharged, the package-carriers 41 are preferably twenty-four in number. These package-carriers are shown 75

in Figs. 3 and 7 as individually pivotally secured to an endless tractor element, preferably an endless chain 59, running on spaced sprockets 60 and 61 (Fig. 7). Sprocket 60 is driven in steps as subsequently described to advance the chain, in steps corresponding in length to the center-to-center spacing of the package-holding pins 12 of a row on the pinboard. As shown in Fig. 3, package carriers 41 as they occupy a straight portion of the path of the chain are closely disposed side by side, their center to center spacing also corresponding to the center to center spacing of the pins of a row.

A bar 63 having both straight and curved portions on which the outer parts of the package carriers 41 ride, is shaped to direct each package carrier into an elevated approximately horizontal position adjacent to the delivery position of the cradle 40, one such package carrier 41 being shown so elevated in each of Figs. 2, 3, 4 and 7. The bar 63 is then curved to allow the package carriers to swing downwardly into an inclined but generally vertical position and pass along a straight path over and across the pinboard, this generally vertical position being adapted for end-wise delivery of the packages onto the pins of the pinboard.

A stationary curved guide plate 65 (Figs. 3 and 7), adjacent to the path of the outer ends of the package carriers, retains the package in its carrier during passage from the elevated position until the carrier arrives above the pinboard. Thereafter, a gate 67 (Figs. 1, 7 and 8) retains the package in the package carrier until the step-by-step advance of the carriers has assembled a group of eight packages over the pinboard above eight pins in a row.

The gate 67 is normally closed but is opened as a consequence of such assembly of a group of eight packages. The gate 67 is carried by arms 68 which are fast on a pivoted shaft 69 (Figs. 7 and 8). A roller 70 (Fig. 8), carried on a crank arm 71 on the shaft 69, normally lies below the lower flat surface portion of a hub 72 turning with the sprocket 60. At the completion of one revolution of the sprocket, which corresponds to the assembly of eight packages over the pinboard, a cut-away portion 73 of the hub arrives over the roller and the roller can then rise into the cut-away portion; the crank arm 71 and shaft 69 then rotating to allow the gate to swing to the right in Fig. 8 or left in Fig. 1, releasing the group of eight assembled packages and allowing them to drop onto the corresponding pins of the pinboard.

In the first part of the next cycle of operation, the gate is restored to closed position by a crank arm 74 which extends from shaft 69 and is engaged by a cam 75 carried by the shaft 53a of the crank disk 53. Following closure of the gate by cam 75, roller 70 is removed from the vicinity of the cut-away portion 73 of hub 72 by one step of the step-by-step rotation of the sprocket 72. Subsequent step-by-step rotation of the sprocket 72 again presents the cut-away portion 73 to the roller 70 when a further group of eight packages has been assembled for discharge.

The relative shift between the pinboard and the package-carriers 41, employed to distribute the packages lengthwise of the pinboard, is preferably accomplished by step-by-step movement of the pinboard past the package-carriers 41.

The pinboards are shown as supported by resting on a pinboard conveyor comprising spaced chains 80 driven as subsequently described and adapted frictionally to urge a pinboard to the

7 right in Figs. 1, 3, and 13 or toward the bottom of the sheet in Fig. 12. Angle pieces 84, 84 are adapted to guide the side edges of the pinboards as they rest on the chains.

Mechanism for detaining a pinboard in position for reception of a row of packages by a row of pins may comprise a pair of hooks 82 each pivotally secured at 84 outside of the angle pieces 84, and each having a widely open mouth at its forward and adapted to engage with the outermost pin 12 of a row. The fulcrum 84 of each hook and the widely open mouth of the hook are so arranged, as will be evident from Fig. 12, that when the hooks are not held in place, as subsequently described, in position to detain the pins, the forward force of the pinboard under the influence of the moving chains 80 can swing the hooks around their fulcrums, disengaging their open mouths from the pins.

Each hook 82 is normally held in its pin-detaining position of Fig. 12, and only released to move out of this position in response to the discharge of a row of assembled packages.

Arms 85 extend downwardly from gate 67 into a position such as shown in Figs. 12 and 13 to engage cam plates 87 extending upwardly from the hooks. As each arm 85 swings to the left in Fig. 13 or toward the upper end of the sheet in Fig. 12, each cam plate 87, which is inclined to the vertical path of swinging of the arm 85, allows its hook to be swung outwardly by the forward force of the pinboard, disengaging the pin of the pinboard. Return of the gate into closed position acts through the arm 85 and cam plates 87 to return the hooks 82 into holding position. However, simultaneously with a return movement of the gate, the chains 80 are advanced one step in their step-by-step movement as subsequently described, which advance of the chains is sufficient to move the last-held pins and their packages beyond the hooks. The hooks next hold pins of the next row of pins on the pinboard, detaining the pinboard in position to receive a further group of packages on this next row of pins. The operation of assembling and positioning the packages continues, and the rows of pins are successively filled with assembled groups of packages.

The step-by-step advance of the package carriers 41 which carries a row of packages into assembled discharging position, is brought about in response to presence at the cradle of the package to be arranged, as detected by the microswitch 57 previously described. This insures that no pin of a pinboard will be left empty even though one or more packages are missing from one or more winding units, because a package carrier does not advance past its package-receiving position unless the cradle receives a package to be placed in the package carrier.

A preferred form of drive for the package carriers and other parts of the mechanism includes a one revolution clutch indicated generally at 90 (Figs. 1, 2 and 11) of which the lower driving member 91 is in the form of a pulley loose upon the main shaft 115 and adapted to be operated by a belt 92 in synchronism with the travel of the winding unit chain 18. The drive to the belt 92 may for example be from gearing meshing with one of the sprocket wheels on which the conveyor chain 18 runs.

An upper driven member 95 of the one revolution clutch is fast on a collar 96 fast on the main shaft 115, and as indicated in Fig. 1, carries a stop

member 97 adapted to be held by a latch 98 to detain the shaft 115 against rotating.

Latch 98 is connected to the armature of a solenoid 110, which as shown in the wiring diagram of Fig. 14, is energized by closure of the microswitch 57. Detection of a package by the microswitch 57 thus causes the latch 98 to be raised, releasing the driven member 95 of the one revolution clutch, and permits the main shaft 115 to rotate through one revolution. Opening of the microswitch 57 as the cradle begins its shifting movement, allows the latch 98 to drop into position to stop the driven member 95 and main shaft 115 at the end of a single revolution.

A single revolution of the main shaft 115 operates the package-delivering cradle 40 by the crank disk 53 and its shaft 53a through one cycle of movement to deliver the package to a package carrier 41 and return the cradle to package-receiving position, and also, following reception of the package by a carrier 41, advances the chain 59 and sprocket 60 and the series of package carriers 41 one step in their step-by-step movement, namely, to the extent of the distance between adjacent pins of a row.

Referring to Fig. 7, shaft 115 has fast thereon near its upper end a gear 117 which meshes with a gear 118 fast on the countershaft 53a. Above its gear 117, shaft 115 extends loosely through the sprocket 60 and its hub 72, and also through the slotted gear 120 of a Geneva movement, slotted gear 120 being fast to hub 72 and sprocket 60. Gear 118 carries the pin element 121 of the Geneva movement cooperating with the slotted gear 120 to impart to the sprocket 60 and hub 72 the above described step-by-step movement.

The above described single-cycle drive which includes the one revolution clutch 90 is preferably also employed to impart an increment of advance to the conveyor chains 80 which advance the pinboards past the package-discharging gate.

Conveyor chains 80 run on sprockets 130 and 131 respectively fast on shafts 132 and 133. An eccentric and eccentric follower 135 are operated by shaft 115 and act through a link 136, crank arm 137, pawl 138 and ratchet wheel 139 to rotate the sprocket shaft 132 in an amount corresponding to one inch advance of the conveyor chains 80 for each package that reaches the cradle 40.

During the major portion of the time that eight packages of a group are being assembled, the step-by-step advance of the conveyor chains beneath the pinboard is an idle movement, the pinboard being detained by hooks 82 as described above.

However the following pinboard, which is to replace the pinboard being filled, is advanced to the right in Fig. 1 at the full rate of advance of the conveyor chains 80 and accordingly is quickly brought into abutting relation to the rear of the receiving pinboard.

The distance between the front row of pins and the front edge of the pinboard, as well as the distance between the rear row of pins and the rear edge of the pinboard is one-half the distance between rows of pins. Accordingly, the distance from the rear row of pins of one pinboard to the front row of pins of the next abutting pinboard is equal to the distance between each row of pins on each board (i. e. one and one-half inches). Abutting pinboards thus present an uninterrupted pattern of pins as one pinboard

replaces the next preceding pinboard in package-receiving position.

The one inch step-by-step advance of the chains 80 is sufficiently long so that when a pinboard is released by the hooks 82, the row of packages just deposited is moved out of the way of the package carriers 41. This step-by-step advance need not be equal to the full distance between rows of pins, namely, one and one-half inches, because the further movement of the chains at the next step-by-step advance can complete the necessary one and one-half inch advance of a pinboard into position to be held by the hooks.

The filled pinboards may be removed from the conveyor chains manually, or may pass off onto any suitable conveyor.

The mechanism preferably includes provision for holding a vertically disposed reserve stack of pinboards to be filled, and provision for withdrawing these from the stack, without jamming or interference, and delivering them to package-receiving position, the withdrawal of the pinboards from the stack taking place in timed relation to the reception of packages and their delivery to a pinboard.

As shown in Figs. 1, 3 and 15, a frame including vertical angle pieces 140 is adapted to receive and confine a vertically disposed stack of pinboards above the conveyor chains 80, some distance in advance of the delivery position of the package carriers 41.

Detents 142 in the form of plate-like elements pivoted at 143 at opposite sides of the stack are adapted to extend in beneath the bottom of a pinboard as best shown in Fig. 15, supporting that pinboard and the other pinboards resting thereon.

An elevator plate 146 movable vertically by a plunger 147, cam follower 148 and cam 149, lies beneath the level of the chains 80 in its lowermost position of Fig. 15. The cam 149 is driven as shown in Fig. 1 by a sprocket 150, chain 151 and sprocket 152 from the shaft 133 in timed relation to the chains 80 and the package-delivering mechanism, so that one revolution of the elevator cam 149 takes place during the delivery of eighty packages to the pins and eighty forward step-by-step movements of the chains 80.

As will be seen from the shape of the cam 149 of Fig. 1, the upward stroke of the plunger 147 and elevator plate 146 is relatively rapid until nearly the top of this stroke. Near the top of the stroke the elevator platform 146 engages the bottom of the pinboard held by the detents 142, removing the pinboard from contact with these detents and lifting this pinboard and the overlying pinboards to the slightly elevated position shown in Fig. 16.

Each detent 142 carries an inwardly extending crank arm 142a; and the elevator plate 146 carries downwardly extending rods 157 having springs 158 resting on enlarged heads 159 at the bottom of rods 157. Upward movement of the elevator platform carries the springs 158 into engagement with the crank arms 142a connected to the detents, tending to lift the crank arms and swing the detents outwardly. The detents are thus swung outwardly to the position of Fig. 16 as soon as the pinboard releases the upper ends of the detents as it is lifted therefrom.

The downward motion of the elevator platform, which is slower than its upward motion, lowers the stack of pinboards, carrying the pinboard which rests thereon below the tops of the detents

142 while these are still held outwardly by the springs 158 as shown in Fig. 17. Further lowering of the elevator platform to its lowermost position of Fig. 15 lowers a pinboard onto the conveyor chains 80. The detents 142 have meanwhile been swung inwardly by the weight of the crank arms 142a into position to engage the next higher pinboard. Thus the bottommost pinboard is separated from the remainder of the stack, and can be removed laterally from the stack without interference by the remaining pinboards.

Figs. 1 and 3 show the bottommost pinboard partly withdrawn from the stack by the chains 80. At this stage this pinboard is partaking of the advance of the chains 80, which advance continues step-by-step, one step for each package, although the preceding pinboard is pausing at the place of discharge of the package carriers while a row of packages is being assembled for delivery. As a result each pinboard is relatively rapidly withdrawn from the stack while the elevator plate dwells in its lowermost position beneath the chains. The pinboard withdrawn from the stack soon clears the stack and advances into abutting relation to the rear of the pinboard which is receiving packages, as diagrammatically shown in Fig. 18, and thereafter advances only at the relatively slower rate at which rows of pins are filled by the package carriers.

After the pinboard has been carried out from above the vertical path of the elevator plate 146, the cam 149 again raises the elevator plate 146 and the next succeeding pinboard is positioned on the chains for removal from the stack.

The machine preferably includes provision for stopping the discharge of packages from the several winding units to the package-arranging mechanism in case of absence of a pinboard, and in the preferred form of mechanism wherein the winding units travel, this is accomplished by stopping such travel and accordingly preventing engagement of the package-discharging crank arms 30 of further winding units with the stationary abutment 31. Further supply of new empty bobbins to the winding units is also suspended by the stopping of travel of the units.

A limit switch indicated generally at 160 in Fig. 1 is urged toward open position, in which position a roller 161 at the end of its actuating arm 162 lies above the bottom of the path of the pinboards. Presence of a pinboard in package-receiving position however depresses the actuating arm, closing the switch 160.

As indicated in the wiring diagram, Fig. 14, limit switch 160 is in series with a switch 164 which is operated by the usual stop button associated with a starting box 167 connected to a three phase power line 168. The starting box 167, controlled by the push button stop switch 164 and limit switch 160 is adapted to de-energize the traveling spindle winding machine and package-arranging mechanism. Thus the clutch solenoid 110, a transformer 170 which supplies current to the conductor rails 20, and an electric motor 171 which drives the chain 18 all become de-energized when the limit switch 160 opens.

The machine may however be re-energized, even though a pinboard is not present, by manually holding the usual starting switch 172 closed. Thus if a pinboard has not as yet reached the limit switch 160, the machine can nevertheless be started and run by holding the starting switch 172 closed, and the pinboard can be caused to advance to package-receiving position wherein it closes the

limit switch 160, whereupon the starting switch 172 may be released.

Figs. 19 to 22 show the application of package-arranging mechanism of this invention to a group of automatic stationary spindle filling bobbin-winding units diagrammatically shown and indicated generally at 180. The mechanism for feeding empty bobbins to the several winding units is omitted for clarity of illustration.

As shown in these figures, each winding unit is adapted to discharge its wound package, tip end first, down a chute 185. The several chutes 185 are curved so that their lower portions discharge their bobbins onto an endless belt conveyor 186, such belt conveyor being suitably driven by an electric motor, not shown.

Conveyor 186 thus carries a procession of the packages from the several winding units endwise to a position alongside and somewhat above the position of the horizontally disposed package carrier 41 of the package-arranging mechanism. In this embodiment the cradle of Figs. 1 to 18 is unnecessary and hence is omitted.

The packages are successively deflected laterally from the conveyor 186 by an inclined guide plate 187 and rolled down an inclined tiltable plate 188 onto the successive horizontally disposed package carriers 41, whereupon the package-arranging mechanism operates to arrange the packages on pinboards as in the previously described form of the invention.

In both illustrated forms of mechanism each cycle of operation of the package-arranging mechanism is initiated by closure of a microswitch 57, which acts to allow a single revolution of the one-revolution clutch 90. However in the mechanism of Figs. 19 to 22 the microswitch 57 is closed by the tilting plate 188 as a package rolls over this plate onto a package carrier. For instance the plate 188 over which the packages roll may be pivotally mounted as shown at 189 in Fig. 22 and carry a downwardly extending crank arm 190 adapted to press against the actuating plunger 191 of the microswitch, so that increased pressure of the crank arm 190 against the plunger, as a package rolls down the plate 188, will momentarily close the microswitch. The microswitch, suitably connected electrically to the solenoid 110, causes the solenoid to remove the latch 98 from the stop 97 and permit a cycle of operation of the driving connections as described above.

The limit switch 160, above described, can be similarly employed in the mechanism of Figs. 19 to 22 to de-energize the driving motors of the plurality of stationary spindle winding units and thus stop winding and also de-energize the motor for the endless conveyor 186 in a manner similar to de-energization of the motor 171 of Fig. 14, when a pinboard is missing from package-receiving position.

We claim:

1. Textile mechanism including a plurality of winding units each adapted to wind a thread package, package-arranging mechanism and means for delivering the wound packages of the several winding units to the package-arranging mechanism, the package-arranging mechanism including a plurality of individual thread package carriers movable in succession to receive individual thread packages, a detector responsive to the presence of a package so to be received, and mechanism controlled by the detector for advancing the plurality of package carriers one step in response to such response of the detector.

2. In a textile machine including a plurality

of bobbin winding units, automatic bobbin-changing mechanism adapted to act upon the several units, and means for causing relative traveling movement between the winding units and the bobbin-changing mechanism, means for collecting the wound bobbins from the bobbin-changing mechanism, means for discharging such bobbins to a plurality of individual bobbin holders, a detector responsive to exhaustion of such bobbin holders to receive bobbins, and mechanism controlled by the detector for disabling the bobbin-changing mechanism upon detection of such exhaustion of bobbin holders.

3. In a textile machine including a plurality of bobbin winding units, automatic bobbin-changing mechanism adapted to act upon the several units and means for causing relative traveling movement between the winding units and the bobbin-changing mechanism, means for collecting the wound bobbins from the bobbin-changing mechanism, means for discharging such bobbins to a plurality of individual bobbin holders, a detector responsive to exhaustion of such bobbin holders to receive bobbins, and mechanism controlled by the detector for stopping said relative traveling movement upon detection of such exhaustion of bobbin holders.

4. In a textile machine including a plurality of bobbin winding units, automatic bobbin-changing mechanism adapted to act upon the several units and means for causing the winding units to travel past the bobbin-changing mechanism, the machine including means for collecting the wound bobbins from the bobbin-changing mechanism, means for discharging such bobbins to a plurality of individual bobbin holders, a detector responsive to exhaustion of such bobbin holders to receive bobbins, and mechanism controlled by the detector for stopping such travel of the winding units upon detection of such exhaustion of bobbin holders.

5. In a textile machine in which pinboards are advanced step by step past package-discharging mechanism, mechanism for holding a vertically disposed stack of pinboards, a conveyor disposed to remove pinboards from the stack and advance the pinboards past the package-discharging mechanism, means operable upon a pinboard on the conveyor at a place where such pinboard has been removed from the stack for detaining such removed pinboard against advancing with the conveyor, the conveyor engaging the pinboards frictionally and being movable forwardly notwithstanding a pinboard on the moving conveyor is detained by said detaining means against forward movement, means for periodically temporarily disabling the pinboard detaining means so as to permit a step-by-step advance of a pinboard past the package-discharging mechanism, driving means for the conveyor operating to advance the conveyor, per each disablement of the pinboard detaining means, a materially greater distance than the extent of the step of advance of a pinboard permitted by such disablement of the pinboard restraining means, the conveyor thereby acting during pauses of a pinboard at the package-discharging mechanism so as to remove a pinboard from the stack in less time than required for step by step movement of a pinboard past the package-discharging mechanism, and means for engaging the next succeeding pinboard of the stack with the conveyor.

6. In mechanism for arranging textile packages, the combination of a surface adapted to establish a path of rolling travel for the packages,

a cradle into which individual packages can roll from said surface, means for shifting the cradle laterally away from its place of reception of a package from said surface and means for tilting the cradle when laterally removed from said place, to roll the package therefrom, a plurality of individual package carriers movable in an endless path to assemble a group of individually-held packages in a row, the carriers being constructed for tilting movement between generally horizontal and generally vertical positions, means for directing the package carriers to a generally horizontal position to receive a package rolled from the cradle, and means for tilting the package carriers to a generally vertical discharging position for endwise discharge of the packages therefrom.

7. In mechanism for arranging textile packages, the combination of a surface constructed and arranged to establish a path of rolling travel for the packages, a cradle into which individual packages can roll from said surface, means for shifting the cradle laterally away from its place of reception of a package from said surface and means for tilting the cradle when laterally removed from said place to roll the package therefrom, a plurality of individual package carriers movable in an endless path to assemble a group of individually-held packages in a row, the carriers being constructed for tilting movement between generally horizontal and generally vertical positions, means for directing the package carriers to a generally horizontal position to receive a package rolled from the cradle, and means for tilting the package carriers to a generally vertical discharging position for endwise discharge of the packages therefrom.

8. Mechanism for arranging wound textile packages upon individual package holders in rows, comprising a plurality of individual package carriers movable in an endless path in a part of which the carriers are aligned with package holders of a row, means for delivering packages to successive carriers at a place in said endless path, single-cycle driving mechanism connected to advance the carriers to the extent of the distance between adjacent package holders of the row, said driving mechanism including mechanism for rendering it ineffective at the end of a single cycle during which such advance of the carriers takes place, a detector for detecting the presence of a package to be arranged, and means controlled by said detector for activating said single-cycle driving mechanism upon the presence of a package to be arranged.

9. Mechanism for arranging wound textile packages upon individual package holders in rows, comprising a plurality of individual package carriers movable in an endless path in a part of which the carriers are aligned with package holders of a row, means for delivering packages to successive carriers at a place in said endless path, single-cycle driving mechanism connected to operate the package-delivering mechanism to deliver a single package to a package carrier, said driving mechanism including mechanism for rendering it ineffective at the end of a single cycle during which such delivery of a package takes place, a detector for detecting the presence of a package to be arranged, and means controlled by said detector for activating said single-cycle driving mechanism upon the presence of a package to be arranged.

10. Mechanism for arranging wound textile packages upon individual package holders in rows, comprising a plurality of individual pack-

age carriers movable in an endless path in a part of which the carriers are aligned with package holders of a row, means for delivering packages to successive carriers at a place in said endless path, single-cycle driving mechanism connected to operate the package-delivering mechanism to deliver a single package to a package carrier and to advance the carriers to the extent of the distance between adjacent package holders of the row, said driving mechanism including mechanism for rendering it ineffective at the end of a single cycle during which such delivery of a package and advance of the carriers takes place, a detector for detecting the presence of a package to be arranged, and means controlled by said detector for activating said single-cycle driving mechanism upon the presence of a package to be arranged.

11. Mechanism for arranging wound textile packages upon individual package holders in rows, comprising a plurality of individual package carriers movable in an endless path in a part of which the carriers are aligned with package holders of a row, means for delivering packages to successive carriers at a place in said endless path, means for discharging packages from a group of the carriers to said row of package holders, conveyor mechanism for advancing the package holders past the discharging mechanism, single-cycle driving mechanism adapted to impart an increment of advance to said conveyor mechanism, said driving mechanism including mechanism for rendering it ineffective at the end of a single cycle during which such single increment of advance of the conveyor mechanism takes place, a detector for detecting the presence of a package to be arranged, means controlled by said detector for activating said single-cycle driving mechanism upon the presence of a package to be arranged, means for detaining the package holders against advance by said conveying mechanism, and means for releasing the package holders to permit advance thereof by the conveyor mechanism after discharge of such group of packages to the row of package holders.

12. In mechanism for arranging wound textile packages from a winding machine of the type including a plurality of winding units traveling in a procession, the package-arranging mechanism being located at one side of the path of travel of the packages of the winding machine, a cradle movable back and forth between a receiving position for receiving a wound package traveling with its winding unit to a delivery position laterally removed from such path, a detector responsive to the presence of a package to be arranged, and mechanism controlled by the detector for moving the cradle through a single cycle from its receiving position to its delivery position and back to its receiving position upon such response by the detector.

13. In mechanism for arranging wound textile packages from a winding machine of the type including a plurality of winding units traveling in a procession, the package-arranging mechanism being located at one side of the path of travel of the packages of the winding machine, a cradle movable back and forth between a receiving position for receiving a wound package traveling with its winding unit to a delivery position laterally removed from such path, mechanism for accumulating a group of wound packages delivered singly by the cradle including mechanism for advancing the packages of said group step by step, a detector responsive to the presence of a package to be arranged, and a single-cycle

driving mechanism connected to operate the cradle and said step-by-step advancing mechanism, the single-cycle driving mechanism being controlled by said detector to actuate the cradle through a single cycle from its receiving position to its delivery position and back to its receiving position and to actuate the step-by-step advancing mechanism for a single step of advance of the packages of said group for each such response by the detector.

14. A winding machine including a plurality of winding units adapted to travel in a procession, means for discharging wound packages from their winding positions in the several units, means for causing the discharged packages to accompany their respective traveling winding units to a place in the path of travel of the units, a generally horizontal cradle adapted to receive individual such discharged packages at said place in the path of travel of the units, means for shifting said cradle in and out toward and from the path of travel of the winding units in timed relation to their travel to receive successive packages, means for discharging a package from the cradle at the outward position of the cradle, a plurality of package carriers, means for moving the package carriers into position to receive individual packages from the cradle at said outward position of the cradle and thence farther outward away from the path of travel of the winding units, means for tilting the package carriers with their packages into generally vertical discharging positions, and a horizontal conveyor for moving pin-

boards step by step beneath the said generally vertical positions of the package carriers to receive groups of packages upon successive rows of pins.
